UNITED STATES PATENT OFFICE.

BENJAMIN PORTER, OF ELLENDALE, NORTH DAKOTA, ASSIGNOR OF ONE-HALF TO FRED L. WALKER, OF SAME PLACE.

OIL-CAN.

SPECIFICATION forming part of Letters Patent No. 554,306, dated February 11, 1896.

Application filed June 7, 1895. Serial No. 551,963. (No model.)

To all whom it may concern:

Be it known that I, BENJAMIN PORTER, a citizen of the United States, residing at Ellendale, Dickey county, North Dakota, have invented certain new and useful Improvements in Oil-Cans, of which the following specification contains a full, clear, and exact description, reference being had to the accompanying drawings, forming part thereof, and in

10 which—

Figure 1 is a central vertical section. Fig. 2 is a detail, and Fig. 3 is a side elevation, partly in section, of a modified form of can.

15 My invention relates to that class of oil-cans which have a piston for forcing the oil through the nozzle or spout.

The object of the invention is to provide such a can with a positive piston-feed and air-inlet mechanism which will be simple and 20 inexpensive and not liable to get out of order.

The invention will first be described and then specifically pointed out in the claims.

A represents the can-body, which is formed 25 in two sections A' A² of sheet metal spun or pressed into the desired shape, the meeting edges of the two sections being soldered or seamed together, as at A³. The section A² is formed with a raised bottom having a piston-rod opening a³ in the apex of its raised portion, while the upper section A' is formed 30 with a cylinder A⁴.

B is a central vertical tube secured at its lower edge to the inner side of the can-bottom concentric with the opening a² and having 35 a similar central opening b in its upper end, said upper end also having air-openings b'. The tube B increases in diameter toward its lower end, and upon this tapering inner tube fits an outer tapering tube C, provided 40 in its upper end with a packing c, which rests upon the upper end of tube B and closes the air-apertures therein.

The outer tube C depends from the lower 45 face of the piston D, having a central rod d, which extends down through the openings b a² and is provided with operating means at its lower end. In Fig. 1 a thumb-piece d' is secured to the lower end of the piston-rod, and this thumb-piece works in the space a formed 50 by the raised portion and normally lies in a

higher plane than the bottom edge of the can, so as not to contact with the surface on which the can rests.

E is a spiral spring, the base or large upper end of which rests against the upper end of the cylinder A⁴, while its lower end rests upon the center of the piston D and presses it down so as to hold the tube C tight upon the inner tube B and also hold the piston normally below the lower end of the cylinder A⁴ to permit oil to flow past the edge of the piston into the cylinder when the can is in position for use. The lower end of the spring is preferably provided with a flat bearing or follower E', so that there will be no danger of lateral slipping.

The upper end of the section A' has the usual threaded collar and into this screws the lower threaded end of the nozzle or spout A⁵.

The parts are assembled before the two sections A' A² are secured together, after which they will require no attention as they all lie within the can out of the way where they cannot become bent or broken.

In Fig. 3 the can is constructed as above 75 described, with the exception that a rim A⁶ is secured to the lower edge of the can and a handle A⁷ attached to one side. The piston-rod d in this construction is operated by means of a lever F, which has a slotted or 80 forked inner end extending between shoulders d² d³ on the lower end of the rod within space a, said lever passing through and pivoted between its ends to the rim A⁶ at f so as to rock vertically. The outer end of the 85 lever F extends up through a slot a⁷ in the lower end of the handle A⁷ and passes through a slot g in the lower end of the plate-spring G, the upper curved end g' of which is secured in the upper end of the handle. Thus when 90 the fingers grasp the spring G and press it toward the handle the upper wall of slot g will bear down on the lever and press its inner end up and cause it to operate the piston-rod d. When the fingers release the spring G, 95 the lower end of its vertical member springs toward the can and the lower wall of the slot g bears on the lower side of the outer end of lever G and thus returns the piston mechanism to its normal position. In this construction the 100

action of the spring G may be supplemented by the spring E, but the latter may be dispensed with if desired.

When the can is turned to permit oil to 5 pass the piston D and flow into the cylinder A' and the lower end of the rod d pressed inward, the piston will be forced into the cylinder and eject the oil, the tube C traveling with the piston and thereby permitting air to 10 enter through openings a² b' and pass into the can through the space now formed between the two tapering tubes. The slight amount of oil that may find its way between the two tubes will be sucked back into the 15 can by the incoming air and by the action of the outer tube C in returning to its place close upon the inner tube. The packing e will still further prevent any escape of oil from between the two tubes.

20 Having thus described the invention, what is claimed is—

1. The combination with the can having a cylinder in its upper end, and a central tube projecting up from its bottom and terminating below the lower end of said cylinder, of a piston having a rod guided in said tube and adapted to be pressed inwardly from the exterior of the can-bottom, and an outer tube moving with the piston and surrounding the 25 inner stationary tube; the said two tubes controlling the admission of air to the can, substantially as described.

2. An oil-can provided with a cylinder in its upper portion and a central vertical tapering air-inlet tube projecting up from the can-bottom but terminating below the lower end of the cylinder, a piston lying normally below the lower end of the cylinder and having an operating-rod extending down through and 30 guided in said tapering tube, and an outer tapering tube moving with the piston and closely fitting the inner stationary tube; said two tubes forming a valve for admission of air to the can when the piston is forced inward and preventing exit of oil in the opposite movement, substantially as described.

3. A can provided with a raised bottom and a cylinder in its upper end, a central vertical tapering air-inlet tube projecting up from the 35 raised bottom, a spring-retracted piston normally lying below the lower end of the cylinder and having an operating-rod guided in the said tube and extending down into the space exterior to the can-bottom, and the 40 outer tapering tube closely fitting over the inner tube, and moving with the piston to admit air through the inner stationary tube substantially as described.

4. A can provided with a raised bottom and 45 a cylinder in its upper end, a central tapering air-inlet tube projecting up from the raised bottom, the piston having an operating-rod extending down through said tube into the space exterior to the raised portion of the can-bottom, and the tapering tube depending from the lower side of the piston and closely

fitting said air-inlet tube; the upper end of the movable tube having a suitable packing to close the upper end of inlet-tube, substantially as described.

5. A can provided with a raised bottom and a cylinder in its upper end, the tapering air-inlet tube projecting up from the can-bottom, a piston normally below the cylinder and having its operating-rod extending down through the said tube, a spiral spring bearing at its upper end against the upper end of the cylinder and at its lower end engaging the piston and forcing it down, the inner movable tapering tube carried by the piston and closely fitting the inlet-tube substantially as described.

6. A can provided with a raised bottom and a cylinder at its upper end, the tapering air-inlet tube projecting up from the can-bottom, a piston normally below the cylinder and having its operating-rod extending down through said tube, a spiral spring bearing at its base against the upper end of the cylinder and having a flat bearing or follower at its lower end or apex engaging the center of said piston, 85 and the movable tapering tube depending from the piston and closely fitting over the air-inlet tube, substantially as set forth.

7. A can provided with a handle at one side, and a cylinder at its upper end, a central tapering air-inlet tube projecting up from the raised can-bottom, a piston having an operating-rod extending down through said tube and can-bottom, a movable tapering tube depending from the piston and closely fitting 100 the air-inlet tube, a lever pivoted between its ends to lower edge of the can, connected at its inner end to the lower end of the piston and extending at its outer end into the space within the handle, and a plate-spring 105 secured within the handle and having an operative connection at its lower end with the said lever, substantially as described.

8. The combination with the can and its piston and air-inlet mechanism, of a lever pivoted between its ends to lower edge of the rim of the can and operatively connected with the lower end of the piston-rod, and a plate-spring depending in the space between the can-handle and body of the can to be grasped by the 110 hand and operatively connected at its lower end with the outer end of the said lever, substantially as described.

9. The combination with the can and its piston and air-inlet mechanism of a lever pivoted between its ends to the lower edge of the can and operatively connected with the lower external end of the piston-rod, and a plate-spring within the handle and having a slot 115 in its lower free end through which the outer 120 end of said lever projects, substantially as described.
